In Great Britain August 26, 1937

4 Claims. (Cl. 61—73)

The invention relates to an improved device for driving boards, planks or the like, e. g. plank-like metal piles into the ground.

In application Serial Number 164,975, there is described a manually operable tool for driving posts and stakes into the ground which consists of an open bottomed guide tube provided with side handles and suitably weighted so that the operator, by sliding it up and down the post to be driven, can use it as a hammer, the tube serving also to guide the post while it is being driven.

When driving planks into the ground, particularly when the planks are used to board a trench, it is frequently necessary to drive each plank in turn a short distance into the ground and this goes on until the trench has been sunk to its required depth. In cases such as this considerable time and effort will be saved if the tool can be shifted from post to post without removing it.

According to the present invention the tool comprises an open sided driving and guiding tube having two or more handles, by which it can be raised and lowered to hammer the board or other post into the ground. Preferably the tool is fitted with guide covers, which are readily detachable therefrom.

In one form the device comprises a member of generally tubular form with one open end, the other end being closed and weighted by a metal plug secured in position by welding or riveting. At each side the tubular member is slotted, and inside it segmental shaped wood blocks are bolted leaving a parallel sided gap in line with the side slots, which slots and gap serve to provide for the entry, accommodation and removal of the plank. Bolted to the top of the member are one or more brackets serving to carry rods or tubes extending outside and down substantially its whole length, being secured near the bottom or open end thereof. These rods or tubes constitute handles for the operation of the tool. These handles may be adapted to be fitted with extension pieces, if extra long planks are to be driven into the ground.

The open slots at the sides are covered by detachable sheet metal guide covers. Each guide cover has riveted near the bottom a lug, which engages over a metal strap fixed near the bottom of the sheath. In this way the guide covers are secured at the bottom by the engagement of the guide cover itself on the inside of the strap and the lug on the outside. The top end of the guide cover is bent over and the bent over portion provided with an elongated aperture. This aperture

is adapted to pass over a spring biased wing nut fitted on a stud screwed into the head of the tubular member, when the wing nut is in one position.

The invention is illustrated in the accompanying drawings, in which Figure 1 is a sectional elevation of a board or plank driving tool constructed in accordance with the invention and showing both guide covers which are detachable in position.

Figure 2 is a plan view of the same but with one guide cover removed and Figure 3 is a sectional plan view on the line 3—3 of Figure 1.

Figure 4 is an elevation showing one of the guide covers removed from the guiding member.

Referring to the drawings, the driving tool comprises a guide tube or member, which may be of any suitable section but which in its preferred form, as shown, consists of a tube indicated generally at 1 open at its bottom end and closed at its upper end, conveniently by a metal plug 2, (see Figure 1) by which the driving tube is weighted. Integral with the guide tube are handles 3, of which four may conveniently be provided, these handles extending throughout substantially the entire length of the unit and if necessary being adapted to be fitted with extension pieces as described in application Serial Number 164,975 previously referred to, should the planks to be driven into the ground be extra long. The handles 3 depend rigidly from crossed bars 3^a rigid with the tube 1. At their lower ends, the handles 3 are rigid with the terminal portions of U-shaped skeleton brackets 3^b rigid on the sections of tube 1.

It will also be understood that alternatively the member may be provided with two or three handles.

According to the present invention, the guide tube is provided down each side with openings, the tube 1 for this purpose being cut away as indicated at A. This permits the driving unit to be applied or removed from the plank to be driven from one side, instead of having to lift it over the top, which may not always be convenient, especially if a series of planks extending side by side have to be driven, in which case it is obviously far easier having driven one plank, simply to remove a guide cover or if necessary both covers, and to slide the device sideways on to the next plank. Wooden blocks 1^a are bolted at 1^b within and to the tube 1.

Detachably secured over the openings A of the driving unit are guide covers B, which may be formed of sheet metal plates having flanged sides

or edges C, the distance between which is such that they overlap the open sides of the guide tube.

5 The guide covers are secured to the driving unit at both their lower and upper ends and for this purpose lug pieces D are riveted to the covers B thereof, the lugs D being adapted to engage straps E fast on each half or side of the guide tube.

10 The straps E, as is clearly shown in Figure 3, are formed with projecting ends F having outward flanges G so as to prevent the covers B from slipping off sideways.

15 At their upper ends, the guide covers B are held by quick release catches, which may take the form of spring controlled studs having interlocking engagement with the covers. The covers B at the top are similarly provided with flanges H consisting of plates having depending walls h' conforming to and secured against the inner surfaces of the upper portions of covers B by welding and over the top plates H are secured bossed plates J, the bosses having dwell portions K. In the plates H and J are elongated aligning slots L.

20 Attached to the block 2 are studs M, on which are mounted spring controlled wing nuts P, the wing pieces Q of which are of a size to pass lengthwise through the slots L but when rotated to the release position shown on the right of Figure 2 engage the dwell portions K in the locking plate.

25 Each guide cover is provided with a handle O so that it can be easily removed.

30 In use, for example when inserting a row of shore boards, one of the guide covers having been removed, the tool is slid sideways over a plank and the cover replaced and secured. The tool is then raised and then pulled down by the handles on to the top of the plank, the process being repeated until the plank has been driven 35 sufficiently far. Care should be taken that the tool does not rebound after each blow, since if so most of the force of the blow is lost. Then, the guide cover or covers according to the extent 40 the board has been driven is or are removed and the tool slid sideways over the next plank without the necessity for raising it vertically completely to clear the first plank. It is a surprising 45 fact that little, if any, injury is done to either end of the planks even when they have to be driven into very hard ground and they may in consequence be repeatedly used as shore boards in trenching or excavating operations.

50 It will be appreciated that the detachable guide covers may be made of thin metal so that the device may be used for inserting a row of closely spaced planks.

55 It will be found that as compared with existing

methods of driving planks into the ground, where considerable damage is done to the ends of the plank sufficient to render them almost useless after one job, with the tool of this invention little, if any, damage is sustained by the posts. 5

It will be understood that while the tool of this invention is primarily intended for driving planks its use is not necessarily restricted thereto and it may be employed for driving posts.

What we claim is:

10 1. A manually operable device for driving planks, boards and the like into the ground comprising a guiding member closed at the top, and having two or more handles extending lengthwise of the guiding member so that it can be caused to slide up and down and operate as a hammer on the plank to be driven, said guiding member having diametrically aligned side openings to permit the sideways entry of or removal of the device from the plank or planks to be 15 driven, and to enable lateral shifting of the device from one plank to another plank when the planks are arranged in rows.

25 2. A manually operable device for driving planks, boards and the like, comprising a tubular guiding member closed at the top and having at least two handles extending lengthwise thereof so that it can be caused to slide up and down and operate as a hammer on the plank to be driven, in which the guiding member is formed 30 with side openings to permit the sideways entry of or removal from the plank being driven, guide covers for the side openings and means for detachably securing said covers to the guiding member.

35 3. A manually operable device for driving planks, boards and the like, comprising a guiding member closed at the top and having at least two handles extending lengthwise of the guiding member so that it can be caused to slide up and 40 down and operate as a hammer on the plank to be driven, said guiding member having side openings to permit the sideways entry of or removal from the plank being driven, guide covers for the side openings, each guide cover and the guiding 45 member having co-operating parts for securing the guide covers to the guiding member in position closing said side openings, and spring means urging engagement of the associated parts.

4. A device as claimed in claim 3 in which the 50 said parts on the guiding member are wing elements engaged by said spring means, the tops of the guide covers having elongated holes for passage of said wing elements therethrough.
